(57) CLAIM

The ornamental design for an infant carrier as shown and described.

DESCRIPTION

1. Infant carrier

1.1: Perspective

The present design relates to an infant carrier. Broken lines show an adult wearing the carrier and an infant carried therein, in order to illustrate the use of the present design; the broken lines do not limit the scope for which protection is sought. Details not visible in the perspective view form not part of the claimed design.
